UNITED STATES PATENT OFFICE.

EARL MARR, OF PHILADELPHIA, PENNSYLVANIA, ASSIGNOR TO MARR OIL HEAT MACHINE CORPORATION, OF MINNEAPOLIS, MINNESOTA, A CORPORATION OF SOUTH DAKOTA.

OIL-FEEDING MECHANISM FOR OIL BURNERS.

Application filed July 3, 1926. Serial No. 120,450.

My present invention relates particularly to oil burners and has for its object to provide highly efficient and reliable means for supplying the oil or fluid fuel thereto. Generally stated, the invention consists of the novel devices, combinations of devices, and arrangement of parts hereinafter described and defined in the claims.

A commercial form of the improved mechanism is illustrated in the accompanying drawings, wherein like characters indicate like parts throughout the several views.

Referring to the drawings:

Fig. 1 is a plan view of the mechanism, 15 some parts being broken away;

Fig. 2 is an end elevation of the parts shown in Fig. 1;

Fig. 3 is a fragmentary view partly in elevation and partly in section on the line 3—3 20 of Fig. 1;

Fig. 4 is a section on the line 4—4 of Fig. 3;

Fig. 5 is a vertical section on the line 5—5 of Fig. 1;

Fig. 6 is a fragmentary view partly in plan but chiefly in horizontal section on the line 6—6 of Fig. 5; and

Fig. 7 is a transverse vertical section taken on the line 7—7 of Fig. 5.

In accordance with this invention, the oil or fluid fuel will be conducted from a source of supply, such as a main supply tank set into the ground, preferably outside of the building in which the burner is installed, 35 through a main oil supply pipe 8 that leads to a pump 9, which, in turn, delivers through a pipe 10 to an auxiliary oil supply tank 11 that is located above the main supply tank. In the pipe 8, there is preferably interposed 40 a cut-off valve 12 and a strainer 13. The pump 9 operates as a primary pump and while it may be of any suitable type, is preferably of the rotary type and, advisably, is of the rotary gear type exemplified in a co- 45 operating secondary pump presently to be described more in detail. At this point, it is only desirable to further state that the rotor of the pump 9 is carried by a shaft 14, which latter directly drives the secondary 50 pump and a centrifugal governor, the structure and function of which will hereinafter be considered.

The casing of the pump 9 has a flanged

base that is bolted or otherwise rigidly secured on a bed casting 15, to which latter 55 the auxiliary tank 11 is shown as rigidly attached by metallic bands 16. The casing of the strainer 13 is also shown as rigidly secured to the base casting 15.

The secondary pump comprises intermeshing gears 17 and 18 arranged to work within the casing 19 that is secured between two head-forming castings or members 20 and 21 by mesh screws 22. The casting 20 is bolted or otherwise rigidly secured to the 60 base casting 15. The casting or member 21 is also formed with a portion that telescopes into and forms a head for a shell 23 that constitutes an oil container and affords a housing for a centrifugal governor 70 presently to be described. The pump-driven shaft 14, which will be driven from a suitable source of power, preferably an electric motor mounted on the base casting 15, is extended from the pump 9 through the pump 75 casing 19 and head-forming members 20 and 21 and projects into the oil container 23.

The pump gear 17 is directly secured to and driven by the shaft 14, and here it may be more definitely stated that said shaft 14 is connected to a corresponding gear of the primary pump 9. An oil pipe 24 extends from the lower portion of the auxiliary tank 11 to the receiving port 25 of the secondary pump, and which port is formed in the pump 85 casing 19, as best shown in Fig. 7. The discharge port 26 of said secondary pump, which is also formed in the casing 19, is connected to a port 27 that leads through the head-forming member 21 to the interior of 90 the oil container 23, (see particularly Figs. 5 and 7). The delivery side of said secondary pump is connected back to the auxiliary tank 11 by a return pipe 29. The pipe 29 is shown as made in two sections connected 95 through a valve casing 30 having a port 31 normally closed by a pressure-opened spring-seated valve 32, (see Fig. 4). This valve 32 is normally closed by a coiled spring 33 that is made adjustable by a plug 34 screwed into the upper end of a sleeve 35, the lower end of which is threaded into the valve casing 30. The numeral 36 indicates a removable cap 100 normally enclosing the projecting end of the plug 34. The receiving section of the return pipe 29, in the arrangement illustrated, 105

- is connected to the port 27 by a port 37, which latter port is shown in Fig. 5. The numeral 38 indicates a pressure gauge connected to the receiving section of the return pipe 29 by a branch pipe 39. The numeral 40 indicates an overflow pipe that extends from the top of the auxiliary tank 11 and leads back to the main tank or source of supply.
- 10 At its extended portion, the oil container 23 is shown as formed with an axially projecting sleeve 41 into which is screwed a tubular member 42, which, at its receiving end, is formed with a capillary or very small oil-discharge passage 43, (see Figs. 5 and 6), that flares toward the interior of the oil container as indicated and constitutes a conical valve seat 44. This capillary oil passage 43 is intended to give a restricted flow 15 of oil to the burner and it delivers through the tubular member 42 to a final oil delivery pipe 45, which latter extends to the burner, not shown. As shown, a normally open valve 46 is interposed in the pipe 45.
- 15 Mounted to slide and to rotate on the reduced end of the pump shaft 14 is a sleeve 47, the end of which is made conical to afford a conical choke valve 48 arranged to closely engage the valve seat 44 and to open 20 and close the restricted oil passage 43. Located within the oil container 23 and secured to and rotatable to pump shaft 14 is a cup-like member 49. A coiled spring 50 surrounds the shaft 14 and reacts at one end 25 against the cup 49 and at its other end against a washer 51 which, in turn, is seated against a shoulder on the sleeve 47. Located within the cup 49 and pivoted thereto at 30 are governor-acting members 53 in the form of weighted levers, the short ends of which engage a shoulder on the sleeve 47. The above noted elements 49, 50 and 53 constitute 35 a centrifugal governor in which the weighted ends of the levers 53 act as the equivalent of the usual "fly balls". To prevent the restricted oil passage 43 from becoming clogged, a fine wire 54 is set axially into the valve 48, as best shown in Figs. 5 and 6, by reference to which it will be noted that when the 40 choke valve 48 is retracted, the free end of the needle or wire 54 will be within the conical valve seat 44 and, although distorted so that it is normally out of axial alignment with the passage 43, will, by the said valve seat, be guided into the said passage when the valve is moved to a closed position indicated in Fig. 5.

Operation.

- 45 All of the running parts are driven by power applied preferably from an electric motor through the pump shaft 14. When a burner having an atomizer of the rotary type is employed, the rotary atomizer will also 50 preferably be driven from the shaft 14.

Here it may be stated that this oil-feeding apparatus or device, while not limited to a specific use, has been especially designed for use in connection with oil burners of the vertical open cup rotary type, such as disclosed and claimed in the King Patent No. 1,158,058, of October 26, 1915, entitled "Centrifugal burner", and in which arrangement, the atomizing cup with attached fan is indirectly driven from a small electric motor, the 75 rotor of which will drive the pump shaft 14 and the said atomizing cup.

When the burner is in action and the shaft 14 is driven, the oil or fluid fuel will be continuously pumped from the supply tank up 80 and into the auxiliary tank 11. This auxiliary tank will be kept filled with oil, for the primary pump 9 will pump oil much faster than it can be burned, so that there is a continuous overflow or return of the oil 85 from the auxiliary tank through the overflow pipe 40 back into the main tank. The secondary pump will pump oil from the auxiliary tank into the container 23 much faster than the oil can be burned and, consequently, 90 the said container will be kept filled with oil and there will be a constant return flow of the oil from said container through the return pipe 29 and back into the auxiliary tank 11. Thus it will be seen that the auxiliary tank 11 and the container 23 will be kept filled with oil under pressure. As already stated, the pressure put upon the oil within the container 23 may be varied by 95 adjustments of the spring 33 of the resistance valve 32, and it, of course, follows that the greater the pressure of the oil in said container, the greater will be the amount of oil forced through the restricted passage 100 43 when the latter is opened by movement of the choke valve 48 out of the valve seat 44 or to position shown in Fig. 6. When the pump shaft 14 has acquired a predetermined speed, the weighted ends of the governor 105 levers 53 will be thrown outward and the choke valve will be moved from its normally 110 closed position shown in Fig. 5 into its open position shown in Fig. 6.

When the motor is cut out and the pumps are stopped, the governor spring 50, acting 115 on the levers 53, will automatically move the choke valve 48 into its closed position. Hence, when the burner is out of action and the pumps are idle, the choke valve 48 positively cuts off the flow of oil from the container 23 to the burner. When the pumps are first started into action, and while they are acquiring the speed required to operate the centrifugal governor, the choke valve 120 will, for a short interval, remain closed, thereby insuring the proper oil-feeding pressure within the container 23 at the time the choke valve is moved to open the feed passage 43.

The use of the two pumping circuits, the 130

- one from the main tank to the auxiliary tank and back to the main tank and the other from the auxiliary tank to the oil container or final oil supply chamber and back to the auxiliary tank, is made highly desirable for various reasons, among which may be particularly enumerated the following: the main tank is, by ordinances of most cities and for other reasons, placed far below the auxiliary tank and frequently a long distance away from the auxiliary tank. In pumping oil from the remotely located main tank to the burner through the long supply pipe, more or less air will become mixed with the oil, and air thus mixed with oil will cause foaming of the oil, and foaming of the oil will render the burning action unsteady and will sometimes cause the flame to be puffed out. With the arrangement here illustrated and described, however, any air pumped from the main tank to the auxiliary tank will be discharged from the auxiliary tank through the overflow pipe 40 that leads from the top of said auxiliary tank. The top of the auxiliary tank, it will be noted, is, in this preferred arrangement, located slightly above the top of the oil container 23 and the oil pipe 24 leads from the lower portion of the auxiliary tank to the receiving side of the secondary pump, so that only oil free from air can possibly reach the secondary pump and container 23. Moreover, when the pump or oil supply means is first started into action, there should be a positive and certain delivery of oil to the burner as soon as the governor has acquired sufficient speed to open the choke valve. This result is attained by the use of two pumps or duplex arrangement of pump circuits. A single pump drawing oil for a long period from a remotely located supply tank would not give this instant or quick delivery of oil to the burner, for the reason that partial vacuum will be produced, resulting in an unreliable and uneven supply of oil, especially during the initial operation of the pump. In the arrangement described, the secondary pump supplies the oil to the container through a short pipe connection, which has a very slight lift so that the delivery of oil from the auxiliary tank to the container free from air will be quick and reliable.
- What I claim is:
1. In a device of the kind described, a container having inlet and discharge ports for the circulation of fluid therethrough, a pump having connections for delivering the fluid to said container, a choke valve for cutting off and releasing the flow through said container, a governor for actuating said choke valve, and means for simultaneously driving said pump and governor.
  2. A device of the kind described comprising a container having inlet and discharge ports for the circulation of fluid therethrough, a rotary pump having connections for delivering fluid into said container, a choke valve normally set to close the discharge port from said container, a centrifugal governor which when operated moves said choke valve to open position, and means for simultaneously driving said pump and governor.
  3. A device of the kind described comprising a container having inlet and discharge ports for the circulation of fluid fuel therethrough, a fluid-fuel-containing tank, a pump having connections for delivering fluid fuel from said tank to said container and from the latter back to said tank, a choke valve normally closing the discharge port of said container, a centrifugal governor which when operated moves said choke valve to an open position, and means for simultaneously operating said pump and governor.
  4. The structure defined in claim 1 in further combination with a resistance valve interposed in the return connection between said pump and tank.
  5. The structure defined in claim 1 in further combination with a resistance valve interposed in the return connection between said pump and tank, and adjustable yielding means for setting said resistance valve under different flow-resisting pressures.
  6. A device of the kind described comprising a fluid fuel tank, a primary pump, an oil supply pipe leading to the receiving side of said primary pump, a conduit connecting the discharge side of said pump to said tank, an overflow pipe leading from said tank, a container having ports for the circulation of fluid fuel therethrough, a secondary pump, a conduit connecting said tank to the receiving side of said secondary pump, said secondary pump being connected for the delivery of fluid fuel into said container, a return conduit connecting the delivery side of said pump back to said tank, a choke valve normally closing the discharge passage of said container, a centrifugal governor which when operated moves said choke valve into an open position, and means for simultaneously operating said primary and secondary pump and governor.
  7. The structure defined in claim 6 in further combination with a yielding flow-resisting valve interposed in the return conduit between said secondary pump and tank.
  8. The structure defined in claim 6 in further combination with a yielding flow-resisting valve interposed in the return conduit between said secondary pump and tank, and means for varying the tension under which said flow-resisting valve may be set.
  9. The structure defined in claim 1 in which said pump has a rotary element and in which said driving means includes a

shaft to which said rotary pump element and said governor are connected for common rotation.

10. The structure defined in claim 1 in which said pump has a rotary element and in which said driving means includes a shaft to which said rotary pump element and said governor are connected for common rotation, and in which said choke valve is a spring-pressed valve slidably mounted on the end of said shaft.
11. A device of the kind described comprising a container having inlet and discharge ports for the circulation of fluid fuel therethrough, a fluid-fuel-containing tank, a pump having connections for delivering fluid fuel from said tank to said container and from the latter back to said tank, a choke valve normally closing the discharge port of said container, a centrifugal governor which when operated moves said choke valve to an open position, and means for simultaneously operating said pump and governor, in combination with a primary pump, a supply pipe extending from a source of supply to the receiving side of said primary pump, a conduit connecting the delivery side of said primary pump to said fluid-fuel-containing tank, and an overflow pipe extended from said tank for the return of surplus fluid to the source of supply.

12. A device of the kind described comprising a container having inlet and discharge ports for the circulation of fluid fuel therethrough, a fluid-fuel-containing tank, a pump having connections for delivering fluid fuel from said tank to said container and from the latter back to said tank, a choke valve normally closing the discharge port of said container, a centrifugal governor which when operated moves said choke valve to an open position, and means for simultaneously operating said pump and governor, in combination with a primary pump, a supply pipe extending from a source of supply to the receiving side of said primary pump, a conduit connecting the delivery side of said primary pump to said fluid-fuel-containing tank, and an overflow pipe extended from said tank for the return of surplus fluid to the source of supply, said primary and secondary pumps having rotary elements connected for common rotation.

13. The structure defined in claim 11 in further combination with a yieldingly closed flow-resisting valve interposed in the connection between the first noted pump and said tank.

In testimony whereof I affix my signature.

EARL MARR.
